EXPLOSION TURBINE

Filed Nov. 10, 1928

UNITED STATES PATENT OFFICE

HANS HOLZWARTH, OF DUSSELDORF, GERMANY, ASSIGNOR TO HOLZWARTH GAS TURBINE CO., OF SAN FRANCISCO, CALIFORNIA, A CORPORATION OF DELAWARE

EXPLOSION TURBINE

Application filed November 10, 1928, Serial No. 318,344, and in Germany November 24, 1927.

My invention relates to explosion turbines and more particularly to the construction of those parts of the turbine which are contacted by the combustion gases. Stated more 5 concretely, my invention involves a novel construction of certain parts of an explosion turbine whereby heat is abstracted from the explosion gases and utilized to superheat steam and also, if desired, to generate it, 10 while at the same time the comparatively thick walls of the turbine frame are protected against excessive heat stresses.

In recognition of the manifold advantages 15 which are afforded by a single or multiple superheating of steam by the waste heat of the gases of an explosion turbine, it has already been proposed by me to effect the superheating of the steam in coils which are arranged in the gas-filled equalizing or 20 exhaust chambers between the individual independent turbine units or explosion turbine stages. Even if whirling of the gas occurs in these equalizing chambers or collectors, and an efficient transference of the 25 heat of the combustion gases to the steam to superheat the latter is thereby favored, with simultaneous cooling of the gases, nevertheless there do not exist in such collectors the high gas velocities which are present in the 30 parts of the turbine through or against which the gases travel; these are therefore quite peculiarly adapted to take up large quantities of heat which may be given up as superheating heat to working steam and it is this 35 property of which my invention takes advantage.

Furthermore, both theory and experience 40 have shown that the parts of the turbine frame contacted by the hot, rapidly flowing gases are subjected to severe thermal stresses due primarily to the rather thick walls of such frame made necessary by the function of resisting the high pressure of the gases, 45 shock, thrust, vibration, etc.; and it is one of the features of the invention that the parts of the frame in the vicinity of the rapidly flowing explosion gases are effectively protected against dangerous heat stresses arising 50 from too great a temperature differential

between the opposite surfaces of the walls composing such parts.

In accordance with my invention, comparatively thin walled cooling chambers or jacketed inserts are built into those parts of the 55 turbine through which the gases travel, such chambers being charged with working steam which is to be superheated. In this way the thick walls of the turbine frame are protected against the direct heating action of the gases by the chambers or inserts whose thin walls, 60 because of the much smaller temperature differential between the opposite surfaces thereof, are not subjected to high thermal stresses. Among the number of individual parts or 65 elements of the turbine which are in contact with the gases, several are particularly distinguished by the fact that the gases which stream past them have extraordinarily high 70 velocities. These elements, at the same time, 75 because of their peculiar location within the turbine, make possible the construction, in a very simple manner, of cooling chambers within which working steam can be superheated. Such a turbine element is, for example, located at the mouth or outlet end of the 80 explosion chamber in which the combustion takes place. In carrying out the inventive idea a jacket defining an annular cooling chamber is arranged about such mouth or outlet. The connecting channel between the mouth of the chamber and the nozzle also presents such a gas heated turbine element 85 through which the gases travel at very high velocity and about which a cooling chamber can be arranged in a simple manner; this channel may therefore be made jacketed or double-walled and arranged, if possible, with an air-space, in the turbine housing, the latter being preferably water or oil cooled. The 90 superheating of the working or live steam takes place in the space defined by the double walls through which it flows. Finally, a cooling chamber may be built into the nozzle itself or the nozzle can be made double-walled; the steam flowing into the cooling chamber or into the space between the double walls effects a cooling of the gases flowing 95 through the nozzle and is at the same time itself superheated. It is within the scope of 100

this invention to arrange cooling chambers simultaneously in different gas heated parts of a single turbine if sufficient wet or saturated steam, produced by the waste heat, especially the waste heat of the exhaust gases and of the explosion chamber walls of the same turbine plant, is on hand for superheating.

In the accompanying drawing which shows 10 by way of example two embodiments of my invention without defining its limits, Fig. 1 is an axial section through a combustion chamber and the associated nozzle, rotor and housing; Fig. 2 represents a similar section 15 through a modified form of my invention.

In both figures the letter *a* represents the 20 explosion chamber in which the explosion of a charge of fuel and air takes place. The main body of the chamber is surrounded by a jacket *b*. In the annular space *u* thus formed a cooling medium, such as water or oil, is circulated; the cooling medium is conducted under pressure to the space *u* by means of the pump *v* which is connected by the conduit 25 *w* with said space. The heat taken up by the cooling medium can be utilized for the production of steam. For example, if water is used as the cooling medium, it may be conducted out of the cooling space *u* through the 30 conduit *x* and then introduced into the coil 1 located in the exhaust space *z* of the turbine, as shown in Fig. 2. The heated water is converted into steam in the coil 1 and is drawn off through the conduit 2 for further 35 utilization. The nozzle valve is indicated at *c* which in its open position permits the gases to travel out of the combustion chamber and through the connecting channel *d* to the nozzle *e*. As the combustion gases discharge 40 from the nozzle *e* or, should the nozzle and channel be made of one piece, from the nozzle-like mouth of the connecting channel *d*, they strike the sets of blades *f* of the turbine wheel *g* and the stator blades *g'* anchored in the 45 turbine housing *h*. The turbine housing is also provided with spaces *i*, *k*, *l*, and *m* for the reception of a cooling medium such as water or oil.

In accordance with the invention (see Fig. 50 1) there is built into each of the turbine elements, such as the combustion chamber outlet *n* and the nozzle *e*, which are traversed by the hot combustion gases, a jacketed insert or cooling chamber *o* or *t*. The cooling chamber *o* is of annular form; its inner wall forms 55 at the same time the combustion chamber outlet. Wet or saturated steam is conducted into the chamber through the conduit 3, which steam is generated by the waste heat of the 60 turbine, as described above (and as shown in Fig. 2) and is then withdrawn by means of pipe 5 in superheated condition. An annular insert or cooling chamber *t* is similarly arranged within the nozzle *e*; wet or saturated 65 steam is charged into the cooling space

through the conduit 4, the steam being produced by the waste heat of the turbine and operating to cool the combustion gases passing through the nozzle *e* after which it is withdrawn through conduit 6 in a superheated state. The conduits 3 and 4 branch out of a single conduit 2 while the pipes 5 and 6 merge into a single conduit 7 which, as indicated by the arrow, conducts the steam independently of the gases to a place of use, such as a steam engine. The cooling medium in chamber *t* also abstracts heat from the combustion gases which fill the turbine rotor space, said heat also serving to superheat the 75 working steam.

As can be seen from the drawing, the walls of the inserts or cooling chambers *o* and *t*, and particularly the inner, gas-swept walls thereof, are considerably thinner than the walls of the turbine frame or housing. As a result, large quantities of heat can flow 85 through such walls from the gases to the cooling agent without creating dangerous heat stresses, since the temperature differential between the opposite surfaces of such gas-swept walls is much lower than in prior constructions wherein the walls of the cooling chambers were made thick as they served simultaneously as the frame of the engine and had to be strong enough to withstand the pressure of the gases, thrust, shock, etc. In my improved construction the heat is conducted largely through the thin walls of the inserts, while the heavier frame walls are 90 protected against the high temperature and 95 stresses due to large temperature differences 100 avoided.

It will be understood that suitable intermittently operated fuel and air charging means (not shown) are associated with the combustion chambers and that suitable igniting means (not shown) may be provided to 105 explode the mixture at predetermined instants, the nozzle valve *c* being forced open by the exploding gases and kept open in any 110 suitable way until the gases, which are under pressure, have escaped from the chamber, streamed through the channel *d* and nozzle *e* and impinged against the blades of the 115 rotor *g*, all as described, for example, in my United States Patent No. 877,194. As these 120 well-known parts of an explosion turbine form no part of my invention I have deemed it unnecessary to illustrate the same.

In Fig. 2 the connecting channel *d* terminating in a nozzle is shown by way of example as the turbine element in contact with the combustion gases which is employed for transferring heat from the combustion gases 125 to working steam. This channel is made double-walled so that an enclosed space *q* is formed around it. The nozzle and channel in this case consist of a single piece wherein the individual cooling spaces are combined to 130 form the continuous space *q*. To the latter

there is conducted, through the conduit 2, wet or dry saturated working steam which is withdrawn in superheated condition through the conduit 7. In order to provide 5 a practicable construction permitting the insertion of the double-walled channel *d* into the water or oil cooled turbine frame or housing *h*, an enlarged space is provided in the latter so that when the channel is in position, 10 there is left an air-space *r* surrounding such channel. Annular discs *s*, *s'*, maintain the channel *d* in position and seal the same. Also a cooling chamber may be arranged about the channel alone, or the chamber outlet alone, 15 and on the other hand cooling chambers may be supplied to all parts of the turbine which are in contact with the hot combustion gases, through which chambers working steam may be conducted to be superheated therein. 20 By the expression "passageway leading from the outlet end of the explosion chamber" as used in the claims, is to be understood the element or elements along which the gases flow at high velocity upon opening of the 25 nozzle valve, such elements including the outlet portion of the explosion chamber and the conduit leading from said outlet portion and constructed and arranged to direct the gases to the place of use.

30 Variations may be resorted to within the scope of the appended claims without departing from the spirit of the invention.

I claim:

1. The combination with an explosion chamber suitable for use in an explosion turbine and adapted to receive intermittent charges of fuel and air which are ignited therein, of a double walled passageway leading from the outlet end of the explosion 35 chamber and arranged to direct the gases to a place of use, the double walls of said passageway defining a cooling chamber for receiving a cooling medium whereby said walls are cooled, said walls being sufficiently thick to 40 withstand the pressure of the gases, shock and other stresses imposed thereon, and a relatively thin walled jacketed insert positioned within said passageway and lining at least a portion of the inner wall thereof so as 45 to be directly contacted by the gases discharging from the chamber and thus protect the thick, cooled wall of such passageway against the high heat of the gases, a conduit for conducting a cooling medium to the jacket of said insert, and a conduit for withdrawing 50 therefrom the cooling medium heated by the heat abstracted from said gases, the thin, inner, gas-swept wall of said insert being 55 adapted to have, during the operation of the explosion chamber, such a small temperature differential between the inner and outer surfaces thereof that no excessive stresses arise 60 therein.
2. The combination as set forth in claim 1 65 wherein the first mentioned conduit conducts

steam into the cooling space of the jacketed insert.

3. The combination as set forth in claim 1, wherein the body of said explosion is provided with a jacket, a conduit for conducting 70 a cooling liquid into said jacket and a conduit for withdrawing the cooling liquid in heated condition therefrom, the jackets of said explosion chamber and said insert being separate, and the conduit leading into the 75 jacket of said insert being connected with a source of steam.

4. The combination with an explosion chamber adapted to receive intermittent charges of fuel and air which are ignited 80 therein, of a conduit for the combustion gases leading from the outlet end of the chamber, at least one jacketed insert lining at least in part the gas passageway defined by said outlet end and said conduit, said passageway being double walled to provide a cooling space for receiving a cooling medium, a jacket about 85 said explosion chamber defining a cooling space, means for conducting a liquid cooling medium into said cooling space, means for generating steam with the aid of the heat contained in said liquid medium, a conduit for conducting such steam into said insert, and a conduit for withdrawing from said insert the 90 steam which has been superheated by the heat abstracted from the gases, the inner gas-swept 95 wall of said insert being relatively thin so that during the operation of the turbine such a small temperature differential exists between the inner and outer surfaces of such 100 wall that no excessive stresses arise therein.
